RUBBER SKI BOOT OR SIMILAR ARTICLE

Maurice C. Smith III, Bristol, R. I., assignor to Bristol Manufacturing Company, Bristol, R. I., a corporation of Rhode Island

Application September 25, 1953, Serial No. 26,953

Term of patent 14 years

(Cl. D7—7)

To all whom it may concern:

Be it known that I, Maurice C. Smith III, a citizen of the United States of America, residing in Bristol, in the county of Bristol and State of Rhode Island, have invented a new, original, and ornamental Design for a Rubber Ski Boot or Similar Article, of which the following is a specification, reference being had to the accompanying drawing, forming a part thereof.

Fig. 1 is a side elevational view of a rubber ski boot showing my new design;

Fig. 2 is a front elevational view thereof, and

Fig. 3 is a top plan view.

Fig. 4 is a rear elevational view of the rubber ski boot.

I claim:

The ornamental design for a rubber ski boot or similar article, substantially as shown.
